ARROWHEAD CONSTRUCTION

John Hauch, Stevensville, Mich.

Application May 23, 1957, Serial No. 661,256

10 Claims. (Cl. 273—106.5)

This invention relates in general to an arrowhead construction and, more particularly, to a type thereof frequently referred to as a "broadhead" and especially adapted for a hunting arrow. This application is a continuation-in-part of my application Serial No. 608,580, filed September 7, 1956, now abandoned.

Persons acquainted with the methods and equipment for hunting wild game with bow and arrow are aware of the fact that special types of hunting tips or arrowheads are required for effective results, particularly where relatively large game is being hunted. Where conventional, relatively streamlined arrowheads are used, it is possible to drive the arrow completely through, or at least well into, a fleshy part of the animal being stalked, without effecting a fatal blow. However, it is recognized that, by proper design of the arrowhead, a penetration made at this same point could produce a fatal injury.

Furthermore, from the humane standpoint, conventional, streamlined arrowheads can strike a relatively critical point in the body of a game animal, which will produce an eventual death, but, because the arrow produces only a small wound with limited bleeding, such death may be hours or days later by which time the animal has travelled sufficiently that the hunter cannot recover its body. On the other hand, an arrowhead which is capable of producing a more rapid rate of bleeding could, by striking this same point in the animal's body, produce a quick and more humane kill, and one where the hunter will more certainly be able to recover the animal's body.

Accordingly, a primary object of this invention is the provision of a hunting-type arrowhead, designed to produce more quickly fatal results than are possible with hunting-type arrowheads presently available.

A further object of this invention is the provision of an arrowhead, as aforesaid, which has excellent penetrating characteristics, which can be easily and effectively resharpened to produce a very keen set of penetrating edges, which is provided with a plurality of surfaces resisting removal of the arrowhead from the game which it penetrates, and which can be used in a substantially conventional manner with conventional arrow shafts.

A further object of this invention is the provision of an arrowhead, as aforesaid, which can be manufactured inexpensively from sheet materials by conventional machines and procedures, and which can be easily and quickly placed upon an arrow shaft by personnel of ordinary skill.

Other objects and purposes of this invention will become apparent to persons familiar with this type of equipment upon reading the following specification and examining the accompanying drawings, in which:

Figure 1 is a plan view of an arrowhead embodying my invention, and shown attached to a fragment of an arrow shaft.

Figure 2 is a side view of said arrowhead.

2

Figure 3 is an exploded, sectional view taken along the line III—III of Figure 1.

Figure 4 is an exploded, front view of said arrowhead.

Figure 5 is a sectional view taken along the line V—V of Figure 2.

Figure 6 is a plan view of a modified arrowhead embodying the invention.

Figure 7 is a sectional view taken along the line VII—VII of Figure 6.

Figure 8 is a leading end view of the modified arrowhead shown in Figures 6 and 7.

Figure 9 is a front view of a further modified arrowhead embodying my invention.

For the purpose of convenience in description, the terms "front," "rear," and derivatives thereof, will have reference to the right and left ends, respectively, of the arrowhead and parts associated therewith, as appearing in Figures 1, 2 and 3. The terms "leading" and "trailing" will have reference to the direction of flight of the arrowhead during ordinary use. The terms "upper," "lower," and derivatives thereof, will have reference to the arrowhead as appearing in Figures 2 and 4. The terms "inner," "outer," and derivatives thereof, will have reference to the geometric center of said arrowhead and parts associated therewith.

General description

In order to meet the objects and purposes set forth above, as well as others related thereto, I have provided 30 an arrowhead 10, preferably having substantially identical upper and lower halves 11 and 12, respectively, both fabricated from relatively stiff and durable material, such as steel, capable of receiving and retaining a sharpened edge. Both halves of said arrowhead 10 have flat, 35 central portions 13 and 14 which are disposed parallel with, and adjacent to, each other. Said upper and lower halves are provided with leading offset portions 15 and 16, respectively, adjacent to, and including, the leading ends of said halves. Said halves 11 and 12 are also 40 provided with trailing offset portions 17 and 18, respectively, adjacent to, and including, the rearward ends of said halves. Said trailing portions combine to provide a recess 19, in which the leading end of an arrow shaft 21 may be snugly received in a conventional manner. 45 Pin openings 22 are provided through said trailing offset portions 17 and 18 for receiving a dowel pin 23, whereby said shaft is held within said conical recess 19. The lateral edges 24 and 25 of said arrowhead 10, including the lateral edges 26 and 27, 28 and 29, of 50 the leading offset portions 15 and 16, respectively, may be sharpened.

Detailed construction

As shown in Figures 1, 3 and 4, the upper and lower halves 11 and 12 of the arrowhead 10, which may be referred to as a "broadhead," are preferably substantially identical. Thus, a detailed description will be directed toward the upper half 11, and such will be understood to refer to both halves 11 and 12, unless specifically stated to the contrary. The leading offset portion 15 has, in this embodiment, a V-shaped cross-section, as shown in Figure 5, produced by the inclined side walls 31 and 32. The lateral edges 26 and 27 of the side walls 31 and 32 are beveled, also as shown in Figure 5, to provide sharp cutting edges, which slope downwardly from the point 33 of the offset portion 15 to the flat, central portion 13. The similarly beveled and sharpened lateral edges 28 and 29 of the leading offset portion 16 on the lower half 12 slope upwardly from the point 34 of said portion 16 to the central portion 14.

The two leading offset portions 15 and 16 (Figure 4), which are prismatically shaped in this embodiment, com-

bine to provide a leading recess 35, which is substantially rectangular in cross-section. This recess 35 is closed by a pair of end walls 36 and 37 on the halves 11 and 12, respectively. The end wall 36, for example, extends between the rearward edges of the side walls 31 and 32 and the adjacent edge of the flat, central portion 13 to close the rear end of the V-shaped groove produced by the leading offset portion 15. The lateral edges of the central portions 13 and 14 are beveled to produce sharp, lateral edges 24 and 25, which constitute rearward extensions of the sharpened, lateral edges 26 and 27, 28 and 29, respectively, of the leading offset portions 15 and 16.

The trailing offset portions 17 and 18 (Figures 1 and 2), like the leading offset portions 15 and 16, may be shaped, as by stamping, in a substantially conventional manner from the sheet material comprising the flat portions 13 and 14, respectively, of the arrowhead 10. The trailing offset portions 17 and 18 include semi-conical portions and, when said halves 11 and 12 are assembled, said semi-conical portions combine to provide a conical shaft recess 19.

The upper and lower halves 11 and 12 are then positioned with their central portions 13 and 14 adjacent to each other, after which they are secured together, as by spot welding. The beveling, which creates the sharpened edges 24, 25, 26, 27, 28 and 29, may be accomplished either before or after the assembly of the upper and lower halves 11 and 12.

When the arrowhead has been fabricated, as described above, it may be easily and quickly mounted upon the leading end of an arrow shaft 21, after which a dowel pin is inserted through the dowel pin openings 22 in the offset portions 17 and 18 and the adjacent portion of the shaft 21, to hold said shaft snugly and firmly within said conical recess 19.

In use, the leading offset portions 15 and 16 of the arrowhead will cut a rectangular opening in the side of the animal and produce a wound of size materially larger than the shaft of the arrow and one which will not close around the shaft of the arrow. Further, the divergent edges 24 and 25 of the arrowhead will cut the wound still wider on either side of said rectangular opening. Thus, the wound will be large, cause very rapid bleeding, cannot possibly close on or around the shaft of the arrow sufficiently to inhibit the bleeding of any material extent and thus will both effect a rapid death of the animal and, by providing a substantial flow of blood, will enable the hunter readily to follow the animal for whatever period of time it remains alive. Thus, the likelihood that the hunter will recover the animal's body is greatly improved as compared with the use of conventional arrows and arrowheads.

Modified structure

The modified arrowhead 41 (Figures 6, 7 and 8), which is generally similar in its appearance and construction to arrowhead 10, described hereinabove, is preferably formed from a pair of identical, relatively flat members 47 and 48. The trailing end portion of the arrowhead 41 has a conical recess 42 into which the leading end of an arrow shaft 43 is snugly receivable. The conical recess 42 is formed by a pair of cooperating semiconical distortions 44 and 45 in the trailing end portions of upper and lower members 47 and 48, respectively, of said modified arrowhead 41.

The leading ends of the upper and lower members 47 and 48 are provided with offset portions 49 and 50, which have triangular cross-sections, as indicated in Figure 8, and which cooperate to define a rectangular recess 52. The recess 52 is here disclosed as having a height, which is substantially greater than its width. This is in contrast to the recess 34 in the arrowhead 10, which is substantially square in cross-section.

It will be observed that the recess 52 is almost completely open and unobstructed at its trailing end, except for the relatively thin central portions 53 and 54 of said

upper and lower members 47 and 48 which extend across the trailing end of the recess 52. Accordingly, any material, such as the flesh of a game animal, which enters the recess 52 through the leading end thereof, as a result of the normal operation of the arrow, can pass through the openings 56 and 57 at the trailing ends of the offset portions 49 and 50, respectively. It has been found that, when an arrow having an arrowhead 41 is in normal flight, air passing through the recess 52 and the openings 56 and 57 imports to said arrow, the stability of a conventional target arrow. This development has resulted in materially increasing both the effectiveness and accuracy of arrows having a modified arrowhead 41, as by comparison with arrows having existing broadheads or hunting arrowheads.

The edges of the central portions 53 and 54 at the trailing ends of the openings 56 and 57 may be sharpened, if desired, to facilitate the operation of the arrowhead 41.

The central ridges 58 and 59 of the offset portions 49 and 50 (Figure 7) may be advantageously converged slightly toward their leading ends in order to provide an expanding cross-section in the recess 52 toward the trailing end thereof. This expanding recess tends to overcome the obstruction, and resultant constriction, produced in the trailing end of the recess 52, by the presence of the central portions 53 and 54, even if they are sharpened. Such a constriction impedes the passage of materials, such as the flesh of an animal, through the trailing end of the recess 52. Furthermore, it is believed that such an expanding section decreases the turbulence of air passing through the recess 52, thereby improving the accuracy and range of the arrow.

As a result of the converging ridges, there is less tendency for the leading offset portions to be spread apart and damaged as a result of impact with a relatively durable object, such as a tree or the bone of an animal. However, it will be recognized that, under some circumstances, the ridges 58 and 59 may be either parallel or somewhat divergent toward the leading end of the arrowhead, particularly where a less efficient or effective performance will be acceptable.

The modified arrowhead 63 is provided with leading offset portions 64 and 65 which are semi-circular in cross-section. In all other respects, the modified arrowhead 63 may be substantially identical to the modified arrowhead 41. Accordingly, the arrowhead 63 has openings 67 and 68 at the trailing end of its recess 69 through which material, such as the flesh of a game animal, can pass as the arrowhead penetrates the animal's body.

Although particular, preferred embodiments of the invention have been disclosed hereinabove for illustrative purposes, it will be recognized that modifications or variations thereof, which lie within the scope of such invention, are fully contemplated unless stated to the contrary in the appended claims.

I claim:

1. Arrowhead structure comprising: an elongated, relatively flat body member having leading and trailing ends and a pair of lateral edges, the major portions of which converge toward said leading end; means defining a substantially coaxial shaft recess in said body member near, and opening toward, the trailing end thereof; a pair of cooperating offset members secured to said body member at the leading end thereof, said offset members defining a cavity substantially coaxial with said recess, each said offset member having lateral edges converging to form a point at the leading ends thereof, the lateral edges of said offset members merging with the lateral edges of said body member.

2. Arrowhead structure, comprising: a pair of substantially identical, relatively flat and elongated members having leading and trailing ends and lateral edges, portions of which are tapered, respectively, toward the leading and trailing ends of said members, said members being rigidly secured to each other in substantially parallel positions; said members having cooperating offset portions near said

trailing ends defining a shaft recess between said members and opening toward the trailing ends thereof; and said members having offset portions near the leading ends thereof defining a recess between said members and opening toward the leading ends thereof, said recesses being substantially coaxially aligned with the lengthwise extent of said elongated members; and said leading offset portions having lateral edges converging to form points at the leading ends of said elongated members and merging with the lateral edges thereof.

3. The structure of claim 2 wherein the recess defined by the leading offset portions is slightly larger in cross-sectional area than the cross-sectional area of said shaft recess near the trailing end thereof.

4. The structure of claim 2 wherein the lateral edges of said elongated members and the lateral edges of said leading offset portions are beveled to provide sharp cutting edges.

5. Arrowhead structure comprising: a relatively flat body member having leading and trailing ends and lateral edges converging substantially throughout their length toward the leading ends thereof; an arrow shaft recess in said body member near, and opening toward the trailing end thereof; a pair of offset members integral with the leading end of said body member and defining a lengthwise passageway in said body member open at both the leading and trailing ends thereof, said offset members being pointed at their leading ends and having lateral edges merging with the lateral edges of said body member.

6. The structure of claim 5 wherein the cross-section of said passageway is substantially rectangular, and the trailing end of said passageway opens on both sides of said body member.

7. The structure of claim 5 wherein said passageway has a substantially arcuate cross-section, and the lateral edges of said offset portions and said body member are sharpened.

8. An arrowhead comprising: a body having a leading and a trailing end, said body also having two pairs of cutting edges, each of said pair of cutting edges defining a point at the leading end of said body, said points being transversely spaced from each other, the edges of each pair of edges diverging with respect to each other and

5
converging toward a corresponding edge of the other pair of edges in a direction toward the trailing end of said body, the corresponding edges of said pairs being joined at a point spaced rearwardly from the leading end of said body.

9. An arrowhead comprising: a body formed of a pair of substantially identical flat elements and having a leading and a trailing end, each of said elements having a first offset portion adjacent the trailing end thereof and 10 having a flat portion extending from the trailing end thereof toward the leading edge thereof, said flat portion having forwardly converging side cutting edges; said elements also having a second offset portion adjacent the leading end thereof, said second offset portion being 15 coaxial with said first offset portion and having a pair of forwardly converging side cutting edges merged respectively, at the trailing end thereof with the side cutting edges of said flat portion and extending away from the plane of said flat portion, said side cutting edges of said 20 second offset portion defining a point at the leading end thereof, said point being offset from the plane of said flat portion; said elements being secured together with their flat portions abutting against each other so that said first offset portions define a recess for receiving an arrow 25 shaft and said second offset portions define a chamber therebetween, said chamber having a pair of transversely spaced points located at the leading end thereof on either side of said flat portions, said chamber opening toward the leading end thereof.

30 10. An arrowhead according to claim 9 wherein the internal walls of said second offset portions converge toward the leading end of said body and means defining openings through the trailing ends of said second offset portions whereby said second offset portions are open 35 at both ends thereof.
